CLAIM

The ornamental design for a latch cover, as shown and described.

DESCRIPTION

FIG. 1 is a front perspective view of a latch cover showing my new design;

FIG. 2 is another front perspective view thereof, with the latch cover being unlocked;

FIG. 3 is a plan view thereof;

FIG. 4 is a rear view thereof;

FIG. 5 is a right side view thereof, the opposite side view being a mirror image; and,

FIG. 6 is another right side view thereof, with the latch cover being unlocked, the opposite side view being a mirror image.
